UNITED STATES PATENT OFFICE.

JOHN INGRAHAM AND ELMER E. NORGAARD, OF COUNCIL BLUFFS, IOWA.

AUTOMOBILE LOCK.

1,412,004.

Specification of Letters Patent. Patented Apr. 4, 1922.

Application filed December 31, 1918. Serial No. 269,167.

To all whom it may concern:

Be it known that we, JOHN INGRAHAM and ELMER E. NORGAARD, citizens of the United States, residing in Council Bluffs, in the 5 county of Pottawattamie and State of Iowa, have invented a new and useful Automobile Lock, of which the following is a specification.

Our invention relates to improvements in 10 automobile locks in which a cut-off is locked in the manifold; and the objects of our improvement are:

First, to provide a locked cut-off in the manifold of an automobile that will successfully stop the running of the engine to 15 which the manifold is applied; second, to provide such a lock without a supporting stem to cause leakage from the outside; third, to provide such a cut-off that will not stick 20 or corrode when in either position; fourth, to provide a cut-off in connection with a commercial lock, so that a complete rotation of the key will furnish the necessary limited 25 rotation of the cut-off; fifth, to provide such a lock, giving the key and turning elements of the lock a leverage over the cut-off; sixth, to provide such an automobile locked cut-off in the manifold that when locked closed 30 will open a cold air duct into the manifold; seventh, to provide a lock having the characteristics herein stated which cannot be opened or removed without removing the manifold 35 or destroying it.

We attain these objects by the mechanism 40 illustrated in the accompanying drawing in which Fig. 1, is a side elevation of a section of a manifold showing an elevation of the lock; Fig. 2, is a side elevation of a section of a manifold showing the lock in position; Fig. 3, is a cross section of a manifold, cut-off and lock. Fig. 4, is a cross section of the manifold and cut-off. Fig. 5, is an elevation of the gear segment and pinion. Fig. 6, is an end view of the cut-off; and 45 Fig. 7, is a cross section of cut-off and manifold showing air duct and stopper.

Similar letters refer to similar parts throughout the several views.

A manifold having the usual connection 50 with the engine block 6 is provided with a suitable cylindrical transverse chamber, *c*. The chamber *c*, is cut away except at two opposite spaces, *a* and *b*, the cut portions of said cylindrical chamber, *c*, corresponding 55 to the hollow portions of the manifold *m*. Into the cylindrical chamber *c* is in-

serted a cut-off *f*, having cylindrical ends and a middle web *w*. The web *w* is adapted to extend between the walls *a*, *b*, of the cylindrical chamber *c*, when the cut-off *f*, 60 is turned in the proper position. The cut-off *f* has formed upon it a gear segment *g*.

This gear segment *g*, is adapted to receive a pinion *p*. Next to the front end of the cylindrical chamber *c* in the manifold *m*, is 65 provided a lock chamber *d*. Chamber *d* or its extension is adapted to receive a commercial lock *l*, of a cylinder and tumbler type, and to be fastened from within the cylindrical chamber *c* by any suitable means 70 as by the screws as shown at *s* in Figure 3, which can only be unscrewed from within the cylinder *c*. The turning member *j*, of this lock *l* enters and engages pinion *p*. The gear segment *g* formed on the cut-off *f* is 75 constructed to limit the travel of the pinion *p*, so that the travel of the cut-off *f* will be proper to open and close the cut-off *f*, in the chamber *c*, and the pinion *p* is so related to the gear segment *g*, that a fraction or 80 multiple of a complete turn of the barrel of the lock *l*, operates to open or close the cut-off *f*. The commercial lock *l*, may be arranged so that the key can be inserted or withdrawn at fractional or full turns of the 85 barrels of the lock; usually at full turns. By so arranging the pinion *p*, and the gear segment *g*, the key of the lock *l*, may be inserted or withdrawn when cut-off *f*, is either 90 in an open or closed position. The pinion *p* is arranged to fit closely into an opening through the wall of the chamber *c*, and a suitable cover *e*, is provided for the chamber *c*, on the back of the manifold *m*, so that the 95 same cannot be removed when the manifold *m* is in position close to the engine to which it is applied. The chamber *c* is thus closed to the ingress of outside air, and removal or operation of the parts are made impossible except by a removal of the manifold from 100 the engine.

In order to insure a failure of operation of the engine when the cut-off *f* is closed in the chamber *c*, we employ an air duct or part *o* here shown in the cover *e* to communicate 105 with the outside air, so that when the cut-off *f*, is closed with the web *w*, extending between the sides *a*, and *b*, of the chamber *c*, any leakage around the cut-off *f*, will be neutralized in the engine by the admission 110 of air through the duct *o*. A suitable cover *h*, is arranged in a suitable place in the cut-

off f , to close the duct o , in the cylinder c , when the cut-off f , is in an open position.

We are able by screwing in such a cylinder c , as a separate part and filling metal or other material back of the portions, a , b , of the cylindrical chamber c , to utilize commercial manifolds securing the cover e , thereon so that the cylinder cannot be removed with the cover e in place or without removing the manifold m .

The operation of the manifold lock is accomplished by inserting the key in the lock l , and turning it a suitable number of turns or portion thereof, so that the pinion p , turns in the segment g , until the web w is turned to its desired position. If the manifold lock with its cut-off f , be closed, the lock can only be turned to open the valve and the pinion p , will move to the extremity of its travel in the gear segment g . The web w , will take the position away from the closed portions a and b , of the cylinder c , allowing the mixture of gases through the manifold m , to pass to the engine. If the cut-off f , be opened, the key may be inserted in the lock and turned until pinion p , reaches the other extremity of its travel, closing the cut-off f . When the cut-off f , is closed, the cover h leaves the duct o open, admitting air through the duct o . When the cut-off is open the cover h , is so placed with reference to the duct o , as to cover it as shown in Fig. 7. The key in the lock may be withdrawn at either extremity of the movement of pinion p , with respect to the gear segment g , thus leaving the cut-off locked in an open or shut position. By reason of the movement of the cut-off f , being a fraction of a turn of the movement of the barrel of lock l , the key in the lock has a leverage over the movement of the cut-off f , preventing the cut-off f , from sticking or holding against the opening of closing of the lock as is the case where the turning

member j , of the lock connects directly with 45 cut-off f .

What we claim and desire to secure by Letters Patent is:

1. In a manifold lock a transverse cylinder in the manifold with a passage formed 50 therein; a cylindrical cut-off having a central cross web; a limited gear segment on the cut-off; a pinion engaging said gear segment, and a commercial lock engaging said pinion.

2. In a manifold lock a transverse cylinder in a manifold with a passage therein; a cylindrical cut-off having a central cross web; a limited gear segment on the cut-off; a pinion engaging said gear segment; a 60 commercial lock engaging said pinion and an air duct leading into said cylinder arranged to be opened when said cut-off is closed and closed when said cut-off is opened.

3. In a manifold lock a cylinder interposed 65 transversely of said manifold, a passage through said cylinder, a chamber adjacent to said transverse cylinder adapted to receive a commercial lock, a means for securing said lock from the inside of said cylinder, a cut-off adapted to revolve in said cylinder and close the passage therein, a gear segment on said cut-off, a pinion operatively positioned intermediate said lock and said gear segment, an air duct leading into 75 said cylinder and means for closing said air duct when said cut-off is open and a removable cover on said transverse cylinder so applied that it fills the space between the end of said transverse cylinder and the engine 80 when said manifold is applied to said engine, so that the same is not removable without removing the manifold.

JOHN INGRAHAM.
ELMER E. NORGAARD.
